Attorney

UNITED STATES PATENT OFFICE.

BERT BENJAMIN HARRIS, OF NEW YORK, N. Y.

SHIP.

1,233,226.

Specification of Letters Patent. Patented July 10, 1917.

Application filed February 23, 1917. Serial No. 150,429.

To all whom it may concern:

Be it known that I, BERT BENJAMIN HARRIS, a citizen of the United States, residing at New York city, in the county of New York and State of New York, have invented certain new and useful Improvements in Ships; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to ships, but more particularly to the deck construction thereof, and has for its object to provide what may be termed a floating or non-sinkable deck so constructed and arranged as will be herein-
20 after described, so that upon injury to the ship bottom from any cause whatever, which would under usual conditions result in the sinking of the ship, the said floating or non-sinkable deck will provide sufficient buoy-
25 ancy to insure the floating of the ship in a manner which will insure the safety of the lives of passengers and cargo thereof.

A further object of the invention is to provide a deck construction for ships so that 30 in case of fire the entire interior of the ship can be flooded through the usual sea-cocks in order to extinguish the fire and without danger of sinking the ship.

With these and other objects in view the 35 invention consists in the novel construction and arrangement of the floating and non-sinkable deck and in the provision for a plurality of gas-tight and hermetically sealed gas tanks, so arranged between the 40 upper and lower deck sections or floors so that said gas tanks will impart sufficient buoyancy to insure the safe floating of the ship under any and all conditions of damage to the hull or bottom thereof.

45 The invention consists in certain other novel details of construction and in certain combinations of parts all of which will be first fully described and afterward specifically pointed out in the appended claims.

50 Referring to the accompanying drawing—
Figure 1 is a plan view of a ship illustrating my deck construction, the top or main deck floor or section being removed.

Fig. 2 is a transverse vertical sectional

view illustrating the deck construction and 55 also illustrating one of the gas tanks positioned therein, and

Fig. 3 is a perspective view of one of the gas tanks.

Like numerals of reference indicate the 60 same parts throughout the several figures, in which—

1 indicates a ship of any form, design or construction and 2 indicates the deck construction thereof.

As will appear from Figs. 1 and 2, the deck construction 2 of the ship includes a lower or bottom floor or deck section 3 extending through the entire ship fore and aft and athwartship thereof, the said bottom 70 floor or section 3 being suitably secured to the athwartship timbers or braces 4 and to the fore and aft sectional timber or braces 5. The said athwartship braces 4 and fore and aft braces 5 are of sufficient depth to accommodate and receive within the compartments 6 the closed or hermetically sealed gas tanks 7, said gas tanks 7 being preferably constructed of a size and shape to snugly fit 75 in each of the compartments 6. I have 80 shown in the accompanying drawing, a gas tank 7 having a plugged opening 8 through which hydrogen gas may be forced to the tank 7 and the said tank closed with a suitable plug to insure the retention of the gas within the tank. Extending over the entire ship and supported upon the athwartship timbers or beams 4 and the fore and aft timbers or beams 3 is a top or upper deck 85 floor or section 9, the said top floor or deck 90 section 9 effectually closing the compartments 6 and retaining the gas tanks 7 in their proper position between the lower floor or deck section 3 and the upper floor or deck 95 section 9.

I provide provision for suitable hatchways 10 through the deck 2, it being of course understood, that the number, location and sizes of the hatch-ways 10 will depend entirely upon the size and nature of the ship. 100

Having thus fully described the invention, its operation will be entirely apparent to those skilled in the art. By the application of a deck constructed in accordance with this invention, either to an existing 105 ship or one originally applied in the ship, will effectually prevent sinking of the ship, even though the hull or bottom of the ship

is ripped, torn or injured to such an extent that the ship under usual conditions would quickly sink.

By the application of my deck construction to ships, the usual water-tight bulkheads are entirely eliminated, which bulkheads experience has shown do not under certain conditions add safety to the ship or prevent its sinking.

10 While I have shown and described what I consider to be the preferred embodiment of this invention, it is evident that the same is susceptible to certain changes in the construction and arrangement of the parts, and 15 I consider myself clearly entitled to all such changes and modifications as fall within the limit and scope of the appended claims.

What I claim as new and desire to secure by Letters Patent of the United States, is—
20 1. A floating or non-sinkable deck for boats, ships and the like, including a series of athwartship beams or timbers, a series of transverse beams or timbers interposed between the said athwartship beams or timbers, 25 a bottom floor or deck section applied under the said timbers an upper or top floor or sec-

tion applied over the said timbers and said bottom, providing between the said deck floors or sections a plurality of compartments and a gas-tight or hermetically sealed 30 gas tank for each of said compartments between the said lower and upper deck floors or sections, substantially as described and for the purposes set forth.

2. A floating or non-sinkable deck for 35 boats, ships and the like, including a series of athwartship beams or timbers, a series of transverse beams or timbers interposed between the said athwartship beams or timbers, a bottom flooring or deck section applied under the said timbers, an upper or top floor or section applied over the said timbers and said bottom providing between the said deck floors or sections a plurality of compartments substantially as described and for 40 the purposes set forth.

In testimony whereof, I affix my signature, in presence of two witnesses.

BERT BENJAMIN HARRIS.
